UNITED STATES PATENT OFFICE.

CLIFTON W. SHERMAN, OF BUFFALO, NEW YORK.

TIE-PLATE.

1,039,453.

Specification of Letters Patent. Patented Sept. 24, 1912.

Application filed December 2, 1910. Serial No. 595,218.

To all whom it may concern:

Be it known that I, CLIFTON W. SHERMAN, a citizen of the United States, residing at Buffalo, in the county of Erie and State 5 of New York, have invented new and useful Improvements in Tie-Plates, of which the following is a specification.

This invention relates to tie plates which are interposed between the undersides of 10 railway rails and the upper sides of ties for the purpose of providing a better support for the rails and reducing the wear on the ties.

One of the objects of this invention is to 15 provide a tie plate of this character which enables the rail to be secured more firmly to the tie and thereby reduce the tendency of the rail to creep under the action of a moving load on the same.

20 Another object of this invention is to provide means which permit of readily assembling the tie, rail and tie plate and thereby facilitate proper installation of the railway.

My invention has the further object to 25 provide a tie plate which will be reliably interlocked with the tie so as to effectually resist any tendency to move laterally relatively to the rail or to rotate about a vertical axis which otherwise would operate to 30 loosen the rail holding means with which the tie plate is provided.

In the accompanying drawings consisting of 2 sheets: Figure 1 is a top plan view of a rail, tie and tie plate showing the manner 35 in which these parts are arranged relatively to each other preparatory to interlocking the tie plate with the rail and securing the rail and tie plate to the tie. Fig. 2 is a similar view showing these parts secured together 40 in their relative operative positions. Fig. 3 is a bottom plan view of the tie plate and the adjacent part of the rail. Figs. 4 and 5 are vertical transverse sections in the correspondingly numbered lines in Fig. 2. 45 Figs. 6 and 7 are fragmentary vertical sections taken in lines 6—6 and 7—7, respectively, in Fig. 3.

Similar letters of reference indicate corresponding parts throughout the several 50 views.

A represents a wooden tie and B a rail both of which are of the usual and well known construction and which are adapted to receive my improved tie plate.

55 C represents the body of the tie plate which is generally of flat form and arranged

horizontally between the upper side of the tie and the underside of the base b of the rail. At two of the diagonally opposite parts on the upper side of the tie plate body 60 the latter is provided with two fastening hooks D, D¹ which are adapted to engage inwardly over diagonally opposite parts of the base of the rail. The body of the plate is also provided at two other diagonally opposite parts of the tie plate body with two spike openings e, e¹ each of which is arranged opposite one of the fastening hooks. These spike openings are adapted to receive the shanks of spikes F, F¹ which are driven 65 downwardly into the wooden tie so that the heads thereof engage over the base of the rail and thereby securely connect the tie, tie plate and rail.

In assembling the parts the tie plate is 70 first placed in an oblique position between the rail and tie so as to permit of passing the base of the rail downwardly between the bills of the fastening hooks D, D¹ and engaging the undersides of the rail with the top 75 of the tie plate body. The distance between the bills of the hooks is just sufficient to permit the base of the rail to be passed downwardly between the same, as shown in Fig. 1. After the rail has been thus deposited 80 upon the tie plate the latter is turned horizontally and about a vertical axis located 85 midway between the fastening hooks so as to carry the bills of the hooks over the adjacent parts of the base of the rail and to engage the backs or shoulders of the hooks 90 with the opposite edges of the rail base. To permit of thus turning the body of the rail properly the underside of the same is provided with a downwardly tapering or conical centering spur or pivot g. After the tie, rail and tie plate have been preliminarily 95 assembled preparatory to being fastened together, as shown in Fig. 1, the pivot or spur of the body is driven slightly into the upper surface of the tie by a slight downward blow upon the tie plate and rail, whereby the tie plate is pivoted on the tie 100 between the fastening hooks thereof. After the spur of the tie plate has been thus driven 105 part way into the tie, the tie plate is turned horizontally on this spur as its vertical axis until the bills of the hooks engage over the upper side of the rail base and the backs of the hooks engage with opposite edges of 110 this base. By thus pivotally connecting the tie plate with the tie it is possible to turn

the tie plate and engage the hooks thereof properly with the base of the rail with facility and without liability of getting these parts out of place relatively to each other and also keeping the tie plate on the central part of the tie where the latter is most efficient in supporting the tie plate and the rail resting thereon.

In addition to the spikes F, F¹ the tie plate is fastened to the top of the tie by means of a locking spike F² which passes through an opening e² formed in a lateral enlargement h of the tie plate body which is arranged adjacent to the outer side of the outer hook D¹ of the tie plate.

In assembling the parts the spike F on the inner side of the rail is first driven home partway leaving the same comparatively loose. The spike F¹ on the opposite or outer side of the rail is then driven fully home into the spike opening e¹ so that its head engages with the adjacent part of the rail base. The relative construction of the rail, spike F¹ and spike opening e¹ is such that the outer side of this spike engages only with the outer side of the spike opening e¹ and the inner side of the shank of this spike engages only with the adjacent edge of the rail base, whereby the opposite edge of the rail base is firmly held or pressed against the back of the opposing hook D of the tie plate. The locking spike F² is now driven fully home through the opening e² of the tie plate and into the tie so that the head of this spike engages with the top of the tie plate and only the inner side of its shank engages with the corresponding side of the spike opening e², whereby the back or shoulder of the adjacent fastening hook D¹ is firmly crowded against the adjacent edge of the rail base. The driving of the first mentioned spike F is completed before the driving of the spike F² is effected so that the head of the spike F bears against the base of the rail opposite to the hook D¹ and the inner side of its shank bears only against the adjacent edge of the rail base and the outer side of its shank bears only against the outer edge of the spike opening e², whereby this side of the rail base is held down upon the tie plate, and the back of the hook D¹ is firmly held against the opposite edge of the rail base. While thus driving the several spikes the pivot spur g is forced fully into the tie so that the underside of the tie plate bears fully against the top of the tie. The driving of the spikes also causes the tie plate to turn slightly horizontally on the vertical pivot spur, thereby increasing the grip of the backs or shoulders of the tie plate hooks on the rail base and effectually resisting the creeping action of the rail.

For the purpose of aiding in resisting lateral displacement of the tie plate on the

tie in all directions the underside of the body is provided with one or more circular anchoring ribs i which are arranged concentrically relative to the pivot spur and are preferably V-shaped in cross section so that they may be easily driven into the top of the tie. Owing to the circular form of the ribs i the same resist lateral strains in all directions and thereby reduce to a minimum the possibility of displacing the plate laterally. The underside of the tie plate is also provided with a plurality of radial anchoring ribs j which preferably connect with the circular ribs, as shown. These radial ribs are also driven into the tie and serve principally to resist turning of the tie plate about its vertical axis in a direction which tends to loosen the engagement of the hooks with the base of the rail. For the purpose of enabling the radial ribs to offer the greater resistance against movement of the hooks away from the rail base these ribs are made ratchet-shaped in cross section, in other words the front side is beveled or inclined and the rear side is straight, abrupt or vertical, as shown in Figs. 5 and 6, which faces are so arranged that the vertical faces receive the thrust which tends to move the hooks away from the rail base and thereby most effectually resist this tendency.

It will thus be noted that my improved construction of tie plate not only provides a substantial bearing for the rail on the tie and reduces the wear on the latter but the same also permits of firmly holding the rail both against lateral displacement when used on curves in the roadway and also minimizes longitudinal creeping of the rail as the cars run over the same.

I claim as my invention:

1. A tie plate adapted to be arranged between a tie and a railway rail comprising a body provided with fastening hooks on diagonally opposite parts of its upper side and with a pivot spur on its underside.

2. A tie plate adapted to be arranged between a tie and a railway rail comprising a body provided on its upper side with fastening hooks and on its underside with a circular anchoring rib.

3. A tie plate adapted to be arranged between a tie and a railway rail comprising a body provided on its upper side with fastening hooks and on its underside with a circular anchoring rib and a radial anchoring rib.

4. A tie plate adapted to be arranged between a tie and a railway rail comprising a body provided on its upper side with fastening hooks on diagonally opposite parts thereof and on its underside with a pivot spur which is arranged between said hooks, and circular anchoring ribs arranged concentrically relatively to said spur.

5. A tie plate adapted to be arranged between a tie and a railway rail comprising a

body provided on its upper side with fastening hooks on diagonally opposite parts thereof and on its underside with a pivot spur which is arranged between said hooks, circular anchoring ribs arranged concentrically relatively to said spur and radial anchoring ribs adjacent to said concentric ribs.

6. A tie plate adapted to be arranged between a tie and a railway rail comprising a body provided on its upper side with fastening hooks on diagonally opposite parts thereof and on its underside with a pivot

spur which is arranged between said fastening hooks and radial anchoring ribs each of which is adapted to enter the tie and each 15 of which is provided with an abrupt rear side and an inclined front side.

Witness my hand this 28th day of November, 1910.

CLIFTON W. SHERMAN.
